TEASING COMB OR THE LIKE

Anton Abraham, Perchtolsdorf, Austria, assignor to Wiener Kammfabrik Anton Abraham Komm. Ges.,
Wiener Neudorf, Austria, a corporation of Austria

Filed Mar. 18, 1963, Ser. No. 74,000

Term of patent 14 years

(Cl. D86—8)

FIG. 1.

FIG. 2.

FIG. 3.

FIGURE 1 is a front elevation of a teasing comb or the like, showing my new design with a portion of the handle shown broken away for convenience of illustration;

FIG. 2 is an edge elevational view taken from the left of FIG. 1;

FIG. 3 is an edge elevational view taken from the right of FIG. 1; and

FIG. 4 is a section along the lines 4—4 of FIG. 1.

The rear elevation of the teasing comb or the like is identical with the front elevation.

I claim:

The ornamental design for a teasing comb or the like, as shown and described.
